US00D883128S

(12) **United States Design Patent** (10) **Patent No.:** **US D883,128 S**
DeYoung (45) **Date of Patent:** **** May 5, 2020**

- (54) **WARNING BEACON FOR VEHICLES**
(71) Applicant: **Innotec, Corp.**, Zeeland, MI (US)
(72) Inventor: **Jonathan R. DeYoung**, Grand Rapids, MI (US)
(73) Assignee: **INNOTECH, CORP.**, Zeeland, MI (US)
(**) Term: **15 Years**
(21) Appl. No.: **35/506,704**
(22) Filed: **Oct. 21, 2018**
(80) **Hague Agreement Data**
Int. Filing Date: **Oct. 21, 2018**
Int. Reg. No.: **DM/200491**
Int. Reg. Date: **Oct. 21, 2018**
Int. Reg. Pub. Date: **May 3, 2019**
(51) LOC (12) Cl. **10-05**
(52) U.S. Cl. **USPC D10/114.8**
(58) **Field of Classification Search**
USPC D10/106.8, 109.1, 111, 114.2, 114.3, D10/114.4, 114.5, 114.8; D26/28, 35, 36, D26/40, 69, 70, 72, 110
CPC F21W 2101/02; F21W 2101/10; F21W 2101/14
